(57) **CLAIM**

The ornamental design for a display screen or portion thereof with icon, as shown and described.

DESCRIPTION

The file of this patent contains at least one drawing executed in color. Copies of this patent or patent application publication with color drawing(s) will be provided by the Office upon request and payment of the necessary fee.

FIG. 1 is a front view of a display screen or portion thereof with icon, showing our new design; and,

FIG. 2 is a front view thereof, in which a display device in broken lines are provided to illustrate an example environment.

The broken lines are for environmental purposes only and form no part of the claimed design.
